UNITED STATES PATENT OFFICE.

CARL R. HELLSTROM, OF MINNEAPOLIS, MINNESOTA.

BAG HOLDER.

Application filed February 9, 1923. Serial No. 618,073.

To all whom it may concern:

Be it known that I, CARL R. HELLSTROM, a citizen of the United States, residing at Minneapolis, in the county of Hennepin and 5 State of Minnesota, have invented certain new and useful Improvements in Bag Holders, of which the following is a specification.

The invention relates to bag holders, and 10 has as an object the provision of improvements upon the device disclosed by the patent granted to me under date of July 25, 1922, No. 1,424,017. A further object is 15 the provision of an improved holder having means for dispensing any of the usual types of bags. A further object of the invention is the provision of supporting means for such bag rack whereby a plurality of racks may be provided to dispense bags of a plurality of sizes.

Illustrative embodiments of the invention are shown in the accompanying drawings, in which

Fig. 1 shows a form of stand with a plurality of holders thereon;

Fig. 2 is a vertical section on line 2, 2 of Fig. 1.

Fig. 3 is a detail vertical longitudinal section of a modified form of holder support;

Fig. 4 is a detail perspective view of the 30 form of device shown in Fig. 3 with the holder removed from its support;

Fig. 5 is a vertical section through a modified form of holder and support.

In the embodiment of the invention shown 35 in Figs. 1 and 2, a support for holders is shown comprising standards 10 and 11 which may desirably be formed of pipe. Bases 12, 13 are shown upon the standards which 40 may be bolted to the floor or counter. Caps 14, 15 are shown which may be utilized for securing of the device in the desired position instead of the bases 12, 13, by bolts passing through the caps into a ceiling, or 45 the under side of any convenient horizontal surface.

The means for directly supporting the 50 holders is shown as a plate 16, which may be stiffened if desired by the provision of a flange 17 extending about its margin. To support the plate 16 upon the standards 10, 11, stirrups 18 may be riveted to the plate and passed about the standards. The plate 55 may then be secured at the desired height upon the standards by means of set screws 19.

The form of the device shown in Figs. 1 and 2 comprises a box or casing 20 open at the rear and having an opening 21 in the lower portion of its front. Preferably the 60 material adjacent the upper margin of the opening 21 is depressed as shown at 22 to efficiently deliver the bags. The box at the lower edge of the opening 21 is provided with a portion 23 rising a short distance 65 from the floor 24 and the edge of the portion 23 is preferably outturned as at 25 to stiffen the same and to provide a smooth delivery member for the lower portion of the bags. To accommodate the excess thickness 70 of the package of bags produced by the folded bottoms thereof, the boxes are desirably made shallower at their upper end than at their lower, as shown. To press the bags toward the opening 21 there is 75 shown a member 26 which may be in the form of a rod guided in a diagonal way 27, shown as comprising a slot in the walls of the box, as disclosed in my former patent referred to.

The weight of the box and contents, in the form of the device shown in Figs. 1 to 4 inclusive, is supported from the rod 26 through the medium of a strap 27 shown as hanging from a hook 28 in Figs. 1 and 2. 80 The hook 28 is shown as passing through a hole 29 in the upper wall of the box and as acting as a guide for the vertical sliding movement of the box as the package of bags therein is reduced in size by removal 85 of bags. It will be seen that the weight of the box and contents supported by the strap 27 will act upon the member 26 to force the same toward the front of the box so as to press the portion of the bags outwardly adjacent the central portion of the opening 21, causing the bags to bulge through said opening. The effect of such bulging is to throw outwardly the folded edge of the bottom of 90 each bag as it becomes exposed, and the bag may be removed from the holder with great celerity by quickly jerking upon the exposed edge of the bottom of the bag.

In the form of the device shown in Figs. 1 to 4 inclusive, means are provided to hold the box in at its bottom and to guide the same in its vertical sliding movement. In the form of Figs. 1 and 2 this guide appears as a hook 30, which may be a duplicate of the hook 28. This hook however has no supporting function but merely serves as a guide and retainer for the bottom edge 100 105 110

of the box. In the form of the invention illustrated in Figs. 1 and 2 the hooks 28 and 30 are duplicated on the opposite sides of the plate 16 and may desirably be formed 5 from a single piece of heavy wire passed through the plate and turned upwardly on the opposite sides thereof. When so formed a series of boxes of the same, or substantially the same, size may be applied to both sides 10 of the plate. Sufficient variation between the boxes on opposite sides of the plate is allowable so that the next size, smaller or larger, box may be placed opposite any particular box. The bags upon the opposite side 15 of the plate from the user may be very readily obtained by extending the hand below the plate 16 and reaching up to grasp the edge of the desired bag.

The form of the device shown in Figs. 20 1 and 2 may be removed by sliding the box upwardly until the holes 29 and 31 are freed from their respective hooks when the box may be pulled away from the plate a sufficient distance to allow the strap 27 to 25 be readily removed. The supply of bags in the box may then be replenished after removal of the member 26 by merely laying the bags in the box, when the box may be replaced by reverse movements.

In the form of the device shown in Fig. 30 4 the guide at the bottom takes the form of a headed plate 32, having a head 33 and a neck 34, the body 35 of the plate is shown as secured to the box by means of a screw 36 passing through the hole 31 in the bottom wall of the box and taking into a threaded hole in the body 35. The guide in the plate 37 is shown in the form of a slot 38 having an enlargement 39 at its top through which 40 the head 33 may be passed in the placing of the box upon the holder. The plate 37 in this form of the device is preferably formed as a pair of parallel separated plates 37, 39, and when so formed the plate 39 may if desired be also provided with slots 38 so that 45 holders may be applied to the opposite surface of a rack, thus formed. This form of the device is preferably mounted upon a hook 28, as in the form of the device first described.

A form of the device for use upon the under surface of a counter, or any convenient horizontal surface 43, is shown in Fig. 55 5, comprising a box made in all respects similar to that already described. To support the box in this position a pair of hooks 40, 41 is shown, that at 41 having a straight member, and that at 40 having its extremity 42 preferably turned upwardly. The box 60 may be placed upon the hook 42 by entry of said hook through the hole 29, with the box depending substantially vertically from the surface 43. When the box is then swung to its position as shown in the figure the wall 65 24 of the box may be pressed inwardly

until it clears the end of the hook 41 when it may be allowed to snap back with the hook 41 engaged in the hole 31.

To press the bags to the front in this form of the device the strap 27 is shown as provided with a weight 44, the strap being otherwise the same as provided in the other forms of the invention, and the action of the delivery of bags in this form of the invention is the same as that already described.

The boxes for each of the forms of the invention herein described will be seen to be identical, and may be formed with the openings 29, 31, which openings are utilized in supporting the box in position in various ways.

To adopt the form of holder above described for dispensing straight bags which do not have the edge of the folded bottom to be projected as shown at 45, the device illustrated in Fig. 3 is supplied. In the embodiment shown herein, this device comprises a false bottom in the form of a plate 46 resting at its rear edge on the bottom of the box and at its front edge upon and terminating above, the lip 25.

To prevent this plate slipping forwardly, a tongue or tongues 47 may be struck downwardly from the material of the plate to lodge behind the portion 23. To retain the lower edges of the bags releasably a tongue 48 is provided which projects forwardly from the front edge of the plate 46 and is preferably upwardly curved to retain the ends. The extremity of the tongue is shown as recurved downwardly to act as a thumb piece. By pressure of the side of the thumb upon the thumb piece, the bottom of a bag may be released to be thrown outwardly by reason of the pressure of bar 26 which bottom may then be grasped and the bag extracted.

The tongue 48 is made of resilient material so as to return to retaining position when released.

Minor changes may be made in the physical embodiment of the invention without departing from its spirit.

I claim:

1. In a device of the class described, a casing comprising end walls, side walls and a front wall, said end walls each having a perforation adjacent its rear margin adapted to receive casing retaining means, said side walls having slots adjacent one end and inclined upwardly and forwardly, said slots adapted to act as ways for feeding means, and said front wall cut away adjacent one end of the casing to provide an opening, a flange upstanding from the end wall adjacent said opening and forming a margin of the opening.

2. A dispensing device for paper bags or the like comprising, in combination, a casing having an opening in its front and openings adjacent the rear edges of its end walls, means at one margin of the front opening

to retain the ends of objects to be dispensed, means in the casing actuated by weight of the casing and contents to move such objects toward the front opening, and means 5 coacting with the openings in the end walls to retain the casing upon a support, for sliding movement.

3. A dispensing device for paper bags or the like comprising, in combination, a casing having an opening in its front and an opening adjacent the rear edge of its upper end wall, means at the lower margin of said first named opening to retain the ends of objects to be dispensed, ways carried by the 10 side walls of the casing adjacent the first named opening, a member slidable in said ways, means for supporting the casing and contents through the medium of said member, means passing through the second 15 named opening to guide the vertical sliding movement of the casing and means to restrain and guide the lower end of the casing for sliding movement.

4. A dispensing device for paper bags or the like comprising, in combination, a casing having an opening in its front and openings adjacent the rear edges of its end walls, means at one margin of the front opening to retain the ends of objects to be dispensed, 20 means in the casing actuated by weight of the casing and contents to move such objects toward the front opening, a plurality of elongated guiding members secured to a support, extending in a plane parallel to the 25 plane thereof and through said openings in the end walls of the casing to retain the casing against the support for vertical sliding movement.

5. A dispensing device for paper bags or the like comprising, in combination, a casing having an opening in its front wall and openings adjacent the rear edges of its end walls, ways carried by the side walls of the casing adjacent the first named opening extending diagonally upwardly and forwardly, a member positioned back of articles to be dispensed and slidable in said ways, a 30 plurality of elongated guiding members se-

cured to a support, extending upwardly in a plane parallel with the support and 50 through said openings in the end walls of the casing to guide sliding movements of the casing, and means supporting the weight of the casing and contents from one of said members whereby objects in the casing will 55 be moved toward said front opening.

6. A dispensing device for paper bags or the like comprising, in combination, a support, a plurality of members passing through and secured to said support, the 60 portions of said members on each side of said support projecting upwardly substantially parallel with the plane of the support and adapted to guide the upper and lower ends of dispensing casings for vertical sliding movements.

7. A dispensing device for paper bags or the like comprising, in combination, a support comprising a plate and standards secured to the vertical edges thereof, a plurality of dispensing casings mounted on said plate for vertically sliding movement, means secured to the plate to guide said sliding movement and means within each casing and attached to the support acting to force objects in the casing into accessible position by means of the weight of the casing and objects.

8. A dispensing device comprising, in combination, a casing having a delivery 80 opening and having a perforation in its top wall, upwardly and forwardly inclined ways carried by opposed walls of the casing, means sliding in said ways to press the contents of the casing to be dispensed, toward said opening, a suspending element secured to said means and having a support engaging opening adjacent its upper end, and a support engaged by said last named opening and extending through said perforation, 85 whereby the weight of the casing and contents may cause said means to slide in said ways as the contents of the casing are depleted.

CARL R. HELLSTROM.
